Primary Examiner — Cynthia M. Chin(74) *Attorney, Agent, or Firm* — Knobbe, Martens, Olson & Bear, LLP(57) **CLAIM**

The ornamental design for a powered wheeled board, as shown and described.

DESCRIPTION

FIG. 1 is a top, rear, left-side perspective view showing powered wheeled board of my design;

FIG. 2 is a bottom, rear, left-side perspective view thereof;

FIG. 3 is a top view thereof;

FIG. 4 is a bottom view thereof;

FIG. 5 is a left-side view thereof;

FIG. 6 is a right-side view thereof;

FIG. 7 is a front view thereof; and,

FIG. 8 is a rear view thereof.

The broken lines illustrate portions of the powered wheeled board that form no part of the claim.
